CLAIM

The ornamental design for a tactical electronics case, as shown and described.

DESCRIPTION

A portion of the disclosure of this patent document contains material which is subject to copyright protection. This patent document may show and/or describe matter which is or may become trade dress of VK Integrated Systems, Inc. The copyright and trade dress VK Integrated Systems, Inc. has no objection to the facsimile reproduction by anyone of the patent disclosure as it appears in the Patent and Trademark Office patent files or records, but otherwise reserves all copyright and trade dress rights whatsoever.

FIG. 1 is a right-front perspective view of a tactical electronics case showing our new design;

FIG. 2 is an exploded view of the right-front perspective view of FIG. 1;

FIG. 3 is a right-rear perspective view thereof;

FIG. 4 is an exploded view of the right-rear perspective view of FIG. 3;

FIG. 5 is a front elevation view thereof;

FIG. 6 is a rear elevation view thereof;

FIG. 7 is a top plan view thereof;

FIG. 8 is an exploded view of FIG. 7;

FIG. 9 is a bottom plan view thereof;

FIG. 10 is an exploded view of FIG. 9;

FIG. 11 is a right side elevation view thereof, the left side elevation being a mirror image of the right side;

FIG. 12 is an exploded view of FIG. 11; and,

FIG. 13 is an exploded left-rear perspective view thereof.

(Continued)

The broken lines depict portions of the tactical electronic case that form no part of the claimed design.
